(57) **CLAIM**

The ornamental design of a cover device for compact fluorescent lamps, as shown and described.

DESCRIPTION

FIG. 1 is a perspective view of a cover device for a compact fluorescent lamp according to a first embodiment;

FIG. 2 is a side view of the cover device shown in FIG. 1;
FIG. 3 is another side view of the cover device shown in FIG. 1;

FIG. 4 is a top plan view of the cover device shown in FIG. 1; and,

FIG. 5 is a bottom plan view of the cover device shown in FIG. 1.
